UNITED STATES PATENT OFFICE.

JOHN M. RATHMELL, OF CONNEAUT, OHIO, ASSIGNOR TO DUNN ROAD MACHINERY COMPANY, OF CONNEAUT, OHIO.

ROAD-MAKING MACHINE.

Application filed August 28, 1924. Serial No. 734,694.

This invention relates to road making machines, for laying concrete pavements, of the type shown in U. S. Patent No. 1,265,499, issued to Allan J. Parish, May 7, 1918, and 5 U. S. Patent No. 1,447,999, issued on my application March 13, 1923.

The object of my present invention is to provide in such a machine a strike-off bar which can be raised and lowered, and which 10 is provided with power actuated means to impart positive longitudinal reciprocation for said strike-off.

Another object of this invention is to provide in such a machine, tamping mechanism 15 which will have positive vertical reciprocation, and provided with means whereby the limits of the vertical reciprocation of said tamping device can be raised or lowered as desired.

20 Another object of this invention is to provide in such a machine a mechanism adapted to trowel finish the surface of the concrete.

These and other features of my invention will be hereinafter fully described and pointed out, and are illustrated in the accompanying drawings in which, viz:

Figure 1 is a plan view of the road making machine embodying my invention.

Figure 2 is a front elevation of the same.

30 Figure 3 is an end elevation of the same. Figure 4 is a fragmentary front view of the crank and clutch mechanism for reciprocating the strike-off plate.

Figure 5 is a side elevation of the same.

35 Figure 6 is a fragmentary front view of the crank and clutch mechanism for reciprocating the finishing trowel.

Figure 7 is a side elevation of the same.

40 Figure 8 is a side elevation of the main transmission gear of this machine.

Figure 9 is a plan view of the same.

Figure 10 is a side elevation of the chain transmission of this machine.

45 Figure 11 is a fragmentary side elevation of the tamper mechanism of my invention.

Figure 12 is a side elevation of a portion of the adjusting lever.

50 Figure 13 is a sectional view of the adjusting mechanism on the line 13-13 in Fig. 1.

Figure 14 is a plan view of the hand-wheel mechanism for lifting the strike-off plate.

Figure 15 is a side elevation of the same.

Figure 16 is a front elevation thereof.

Figure 17 is a vertical longitudinal section of the differential clutch mechanism for 55 operating the traction drive shafts.

Figure 18 is a side elevation of the same showing both sides thereof opened.

Figure 19 is a side elevation of one of the 60 hinged brackets.

In these drawings A indicates the usual side forms for the pavement, upon which the machine travels as hereafter described, and 65 between which the concrete is laid.

A' indicates the traction wheels upon 70 which the end frames A² of the machine are mounted.

The end frames A² are tied together by 75 means of a frame consisting of transverse beams B and end beams B' which are secured together by means of castings B², the ends of which project under the side frames A² to which said castings are secured by means of bolts b. The frames A² and B, B' 75 are similar in construction to the frame of the machine shown in the Letters Patent heretofore mentioned, and therefore form no part of this invention.

The traction wheels A' at each end of the 80 machine are connected by means of sprocket wheels a and a chain a', see Fig. 3, so that said wheels at each end of the machine will revolve in unison and the motive power of the machine is applied to both.

85 Mounted on the machine frame is a traction driving shaft C which is divided, and is provided with a double faced clutch C', see Figs. 17 and 18.

In this clutch, a sprocket wheel C² is 90 rotatably mounted upon and overlaps the meeting ends of the shaft C where it is held in place by means of collars cc secured on said shafts by means of set screws c'. The hub of the sprocket wheel C² is recessed to receive the collars cc and the annular edges of the hub are cut away to form clutch shoulders c² as shown in Fig. 18.

95 Slidably mounted on the shafts C at each side of the sprocket wheel are clutch sleeves C³, the shafts C being provided with keys c³ to prevent said sleeves from rotating upon said shaft.

100 The sleeves are provided with clutch shoulders c⁴ adapted to engage the shoulders cc on hub of the sprocket wheel C². The sleeves

C³ are adapted to be independently operated by the levers C⁴ and C⁵, see Figs. 1 and 2, the right hand lever C⁵ controlling the right hand portion of the divided traction shaft C and the left hand lever C⁴ controlling the left hand portion of said shaft, so that when it becomes desirable to advance one end of the machine with relation to the opposite end, one or the other lever C⁴ or C⁵ can be used as desired.

The outer ends of the divided shaft C are provided with sprocket wheels c⁵, and upon the shaft of traction wheel A' at each end of the machine is placed a sprocket wheel A³, said sprocket wheels c⁵ and A³ carrying chains A⁴ see Figs. 1 and 3, so that power from the traction shaft C is communicated to the four traction wheels A' of the machine.

I provide a reversing transmission gear D, see Figs. 8 and 9, which is composed of a pair of shafts D' and D², mounted in suitable bearings. The shaft D' is provided with a sprocket wheel d by means of which power is applied to the shaft D'. Upon the shaft D' are placed spur-gear wheels D³ and D⁴, each of said wheels being provided with clutch collars d' and d², said wheels being rotatable upon the shaft D'.

Between the clutch collars d' and d² there is a slideable clutch sleeve D⁵, which is non-rotatable on the shaft D' by reason of the key d³ so that the clutch can be slid on the shaft D' so as to cause either spur-wheel D³ or D⁴ to rotate with the shaft D'.

Mounted upon a stud-shaft E is an idler spur gear wheel E' which meshes with the spur wheel D⁴, as shown by broken lines in Fig. 8.

Upon the shaft D², see Fig. 9, is fixed a spur-wheel E² which meshes with the spur-wheel D². There is another spur-wheel E³ fixed on the shaft D² which meshes with the idler spur-wheel E, so that when the clutch sleeve D⁵ is engaging with the wheel D⁴ the shaft D² and spur-wheel E will revolve in the same direction as does the shaft D', with spur-wheel D³ revolving freely on the shaft D', and when the clutch sleeve D⁵ is slid into engagement with the gear pinion D³, the gear spur D⁴ will revolve freely on the shaft D' and the shaft D² will turn in a direction opposite to the shaft D'.

On the shaft D², see Fig. 9, is fixed a sprocket wheel E⁴, from which a chain E⁵, see Fig. 10, extends around the sprocket wheel C², see Figs. 1, 17 and 18, by means of which chain E⁵, the traction shaft C is driven.

Mounted in the machine is a tamper shaft F, see Figs. 1, 2 and 10, upon which are placed tamper operating eccentrics F', see Figs. 1, 2 and 11.

Upon the tamper shaft F is a friction clutch mechanism F² of ordinary construc-

tion, which is provided with a sprocket-wheel f, upon which a chain f' is placed which extends over a like wheel f² on the shaft G of the motor G'.

Upon the hub of the friction clutch mechanism F² there is also another sprocket-wheel f³ and over this wheel and the sprocket wheel d on the shaft D', see Fig. 9, a chain f⁴ is placed, so that power will be communicated from the engine shaft G to the tamper shaft by the chain f', and from the tamper shaft to the transmission shaft D' by the chain f⁴, see Fig. 10, and from the transmission D, see Fig. 9, to the divided traction shaft C by the chain F⁵ see Fig. 10.

For operating the clutch sleeve D⁵ a lever D⁶, see Figs. 1 and 2, is provided, by means of which the power transmitted to the traction shaft can be controlled to cause the machine to travel forward or backward on the side forms A, as may be desired, the gears of the transmission D, see Figs. 8 and 9 being so proportioned that the backward travel of the machine will be faster than its forward travel.

The mechanism hereinbefore described is designed for the purpose of conveying and operating the strike-off, tamping and finishing mechanisms of my invention hereinafter described, viz:

The strike-off.

H, indicates a strike-off bar which is suspended in front of the machine upon rock-shafts H', see Figs. 1 and 2, mounted upon the side beams A², by means of crank arms h and link bars h'.

The rock-shafts H' are provided with crank arms H² to which rods H³ are pivoted which extend to hand-wheel mechanism J, see Figs. 14, 15, and 16, in which they are pivoted to the ends of a cross lever h³ which is fixed upon a vertical shaft H⁴ mounted in a suitable frame H⁵ which is secured upon beams B³ of the machine frame. Fixed upon the upper end of the shaft H⁴ is a hand-wheel by means of which the shaft H⁴ can be operated to lift the strike-off bar H when desired. In order to retain the strike-off bar in a raised position a ratchet segment h⁴ is fixed upon the vertical shaft H⁴ and a ratchet lever h⁵ is pivoted in the frame H⁵ adapted to engage the ratchet segment to retain the segment and strike-off bar H in its raised position.

To support the strike off bar H against the forward thrust of the machine, hinge-brackets J' see Fig. 19, are provided, which are pivoted to the rear side of the strike-off bar H by means of pivot pins j, which are long enough to permit the strike-off plate to slide vertically thereon.

The rear ends of the hinge-brackets J' are pivoted to ears J² secured upon a beam B³ of the machine frame, by means of pivot pins

j'. The hinge-brackets *J'* permit the strike-off bar *H* to be reciprocated longitudinally as hereinafter described.

The tamper.

Behind the strike-off bar *H* is placed a vertically reciprocating tamping bar *K*, see Figs. 3 and 11, which is suspended upon the free ends of oscillatory levers *K'*. The levers *K'*, see Fig. 11, are fulcrumed upon eccentrics *K*² which are rotatably mounted upon stud-shafts *K*³ secured in the supporting brackets of the traction shaft *C*. Secured upon the eccentrics *F'* on the tamper shaft *F* are eccentric straps *F*³ from which arms *F*⁴ extend and are pivoted to the lever *K'*.

Tamper adjusting mechanism.

The eccentrics *K*² are each provided with an arm *K*⁴, to which a link-bar *K*⁵ is pivoted.

Rotatably mounted on the machine frame is a shaft *k* which extends longitudinally under all of the oscillatory levers *K'*. Adjacent to each of the eccentrics *K*² an arm *k'* is fixed upon the shaft *k*, which arm *k'* is pivoted to the link-bar *K*⁵.

For operating the eccentric *K*², an arm is fixed upon the shaft *k*, at the intermediate portion thereof, to which a link-bar *k*³ is pivoted which extends to an operating lever *k*⁴ to which it is pivoted. The lever *k*⁴ is fulcrumed upon a bracket *k*⁵ which is provided with a notched segment *K*⁶, see Fig. 12, with which a latch *k*⁶ engages.

The lever *k*⁴ can be operated to rock the eccentric *K*² upon the stud-shaft *K*³ changing the position of the lever *K'* from its position shown in full lines in Fig. 11, to the position shown in broken lines, thus raising the tamper *K* as shown in broken lines, the lever *k*⁴, through the shaft *k* operating all of the eccentrics *K*² in unison, while the rotation of the eccentrics *F'* continues the vertical reciprocation of the tamper bar *K*.

The tamper bar *K* is secured upon vertical screw-threaded rods, see Fig. 11, upon which is placed a spring *L'* which is held upward thereon by means of a nut *L*² so that said spring presses against the lever *K'*, so that the downward pressure of the lever *K'* upon the tamper *K* will be cushioned by the spring *L'*. A link bar *L*³ is pivoted to the tamper *K* and to a beam *B*³ of the machine frame to prevent lateral movement of the tamper.

The finishing trowel.

Behind the tamper bar is suspended a finishing bar or trowel, *M* which is provided with parallel links *m* adapted to draw it forwardly as the machine travels ahead, and which parallel links *m* operate to maintain the finishing bar *M* in an upright position, see Figs. 3 and 7. To lift the finishing bar *M* upward, clear of the work, cables *M'* are

attached thereto, which cables *M'* pass over pulleys *m'* see Figs. 1 and 2, and lead to a windlass mechanism *M*², which is provided with a hand wheel, see Figs. 1 and 2, by means of which said finishing bar *M* can be raised when desired. The finishing bar *M*, being suspended upon the cable *M'* and parallel links, *m*, is free to receive horizontal reciprocation by means of the mechanism hereinafter described. 75

The finishing belt.

For the purpose of smoothing the surface of the concrete, a fabric belt *N* is provided which is stretched upon a frame *N'* slidably supported upon brackets *N*² secured upon the side beams *A*² of the machine. This belt *N* is caused to reciprocate longitudinally as the machine moves forward, and is provided with an arm *N*³ from which a bar *N*⁴ extends 85 forward to the frame *N'* where it passes through a slotted bracket *N*⁵ so that by pulling the bar *N*⁴ forward the frame *N'* and belt *N* can be turned upward clear from the work. 90

Reciprocating mechanism.

Transversely mounted upon the frame of the machine is a shaft, *O*, see Figs. 1, 5, 6 and 7, upon which is fixed a mitre gear, *O*¹ 95 which meshes with a like gear *O*² on the shaft *D'* of the transmission gear *D*, see Fig. 9, and on the front end of the shaft *O*, is secured a crank *O*³ upon which a pitman *O*⁴ is placed, which extends and is pivoted to the strike-off bar *H*, see Figs. 1 and 2.

A clutch mechanism *P*, see Fig. 5, is provided, by means of which the revolution of the crank *O*³ can be stopped. A lever *P'* is provided for opening said clutch, which lever is operated by raising the strike-off bar upwardly until the inverted *U*-rod, *p*, engages the lever *P'* and opens the clutch. A spring *p*² is provided to close the clutch when the strike-off bar is lowered. 110

Upon the transverse shaft *O* is fixed a spur gear *Q*, see Figs. 1, 6 and 7, and mounted in suitable bearings on the machine frame parallel with the shaft *O*, is a crank-shaft *Q'*, having a crank *Q*² thereon upon which a 115 pitman *Q*³ is placed, which extends and is pivoted to the finishing bar *M*. A spur wheel *Q*⁴ on the crank shaft *Q'* meshes with the spur wheel *Q* on the shaft *O*.

A clutch *Q*⁵, see Fig. 7, is provided, with 120 an operating lever *Q*⁶ adapted to be engaged by the finishing bar *M*, when the same is raised clear from the work, as described, to open the clutch *Q*⁵ to stop the reciprocation of said bar.

Upon the rear end of the transverse shaft *O* is placed a crank *R* upon which a pitman *R'* is placed which is rotatably secured to the belt frame *N'*. A clutch *R*² is provided on the shaft *O*, which has an operating lever, 130

see Figs. 1 and 3. A slotted bar R^4 , is pivoted to the clutch lever R^3 and to the bar N^4 , so that when the belt N is raised from the work, the bar R^4 will operate the lever R^3 to open the clutch R^2 and thereby stop the reciprocation of the belt.

In operation the space between the side forms A is filled with wet concrete. The motor G' is started. The strike off plate H 10 is lowered upon the side forms. The finishing bar M is lowered upon the side forms. The clutch mechanism F^2 is closed to cause the tamper shaft F to rotate and the tamper K to reciprocate vertically. The lever D^5 is 15 then operated to cause the transmission gear mechanism D to move the machine forward. The shaft O is now causing the strike-off H , the finishing bar M to reciprocate longitudinally, which scrapes the mass of concrete 20 between the side forms A to the desired contour, which is tamped down by the vertically reciprocating tamper bar K , and the surface trowelled off smoothly by the longitudinally reciprocating bar M being 25 drawn over it by the advancing machine. During this operation, if it is desired the surfacing belt N can be lowered upon the concrete, and the clutch R^2 will close thereby causing said belt to commence its reciprocation as it contacts with the concrete 30 while it is being carried forward over the same.

If it is necessary to back the machine up, the belt N is raised which stops its reciprocation. The smoothing bar M is raised and its reciprocation stopped. Likewise the strike-off bar H . The traction shaft C stopped.

The tamping shaft should be stopped in its rotation by the opening of the clutch 40 F^2 with the tamper K in its raised position. For this purpose, and to counter-balance the weight of the tamper K , counter-weighted wheels S are provided on the shaft F , which can be grasped and the shaft F 45 revolved manually until the tamper is raised clear from the work, when the lever D^5 can be operated to reverse the travel of the machine.

Having thus fully described the construction of a machine embodying my invention so that others can utilize the same, I am aware that many modifications can be made therein without departing from the scope of 50 my invention.

Therefore, what I claim as new and desire to secure by Letters Patent is:

1. In a machine of the class described, a strike-off bar, means to raise and lower said bar, a shaft, a clutch on said shaft, a crank operated by said clutch, a pitman mounted 60 on said crank and pivoted on said strike-off bar, a bell-crank-lever to open and close said clutch, and means on said strike-off bar to engage said bell-crank-lever and open said clutch when said strike-off-bar is raised. 65

2. In a machine of the class described, a machine frame, rock-shafts mounted on said frame, lever arms on said rock shafts, a strike-off-bar, links pivoted on said lever arms and to said strike-off-bar, a hand wheel 70 shaft, a cross-bar on said hand wheel shaft, link-rods pivoted on said cross-bar and to lever arms on said rock-shafts, and ratchet and dog mechanism to prevent backward movement of said hand wheel shaft. 75

3. In a machine of the class described, a travelling machine frame, longitudinally swinging brackets pivoted on said frame, vertical pivot pins in the free ends of said brackets, a strike-off bar vertically slidable 80 on said pivot pins, manually operated means to raise and lower said strike-off bar on said pivot pins, and mechanism to impart longitudinal reciprocation to said strike-off bar. 85

4. In a machine of the class described, a vertically shiftable fulcrum, a lever mounted on said fulcrum, crank and pitman mechanism adapted to oscillate said lever, and a tamper suspended on said oscillatory lever. 90

5. In a machine of the class described, an eccentric mounted on said machine, lever and link mechanism to shift said eccentric, an oscillatory lever fulcrummed on said eccentric, shaft and eccentric mechanism to oscillate said lever and a tamper bar suspended 95 from the free end of said lever.

6. In a machine of the class described, a series of eccentric fulcrum pivots mounted in said machine in horizontal alignment, lever, link and shaft mechanism adapted to 100 shift said eccentric fulcrum pivots in unison, a series of levers mounted on said fulcrum pivots, shaft and eccentric mechanism to oscillate said levers in unison, and a tamper bar suspended on the free end of said lever. 105

In testimony whereof I affix my signature.

JOHN M. RATHMELL.
